UNITED STATES PATENT OFFICE

CHESTER A. HARSON, OF NEWTON, MASSACHUSETTS, ASSIGNOR TO SARASONE SCREEN COMPANY, OF BOSTON, MASSACHUSETTS, A CORPORATION OF MASSACHUSETTS

PROJECTION SCREEN FOR MOTION PICTURES

Application filed November 26, 1929. Serial No. 409,981.

This invention relates to reflecting screens and has particular reference to screens for use in motion picture theaters which employ so-called loud speakers behind the projection screens for the transmission of speech and music through the screens to the audiences.

The increasing popularity of the so-called sound pictures or "talkies" calls for the closest possible approach to perfection in the projection screens so that they not only will properly reflect all details of the pictures but also offer the least possible obstruction to the transmission of sound of all kinds through the screens.

One kind of material heretofore employed for projection screens is composed of canvas or duck fabric coated with aluminum and bronze powders. Such material interferes with the transmission of sound. Another kind of material employed consists of cotton threads woven with sufficient looseness to permit the transmission of sound through the fabric. This fabric, however, does not reflect pictures entirely satisfactorily, and the large amount of soft cotton seems to absorb some of the sound.

Another kind of material proposed consists of a fabric including metallic threads, which fabric is rolled to crush the metallic threads, but such fabric is not well adapted for use in connection with what are known as sound pictures, as it is too finely woven, and the crushed metal interferes with the transmission of sound.

Another kind of material proposed consists of all polished metal strands or wires of double convex form in transverse section, closely interwoven, but such material is too bright for many pictures, and interferes with the transmission of sound.

One of the objects of the present invention is to provide an improved screen for the purposes explained, which screen presents a great multitude of very fine dots of material which are made luminous by the rays of light from a motion picture projector and therefore effect reflection of all details of the picture.

Another object is to provide a satisfactory reflecting screen that offers the least possible

obstruction to the transmission of sound through it.

With the above mentioned objects in view, and others hereinafter explained, the invention consists in the construction and combination of parts substantially as herein-after described and claimed.

Of the accompanying drawings:

Figure 1 is an elevation of a motion picture screen embodying my invention, with portions broken out to indicate that it may be of any desired dimensions.

Figure 2 is an enlarged face or front elevation of a small portion of the reflecting screen fabric.

Figure 3 represents a section on line 3-3 of Figure 2.

Figure 4 is a view similar to Figure 2 but taken from the rear of the fabric.

Figure 5 represents a section on line 5-5 of Figure 2.

Similar reference characters designate similar parts or features in all of the views.

The fabric of my improved screen, of the specific woven type illustrated by the drawings, consists of weft and warp threads, one of the series of threads consisting of rather soft fibrous material and those of the other series consisting of bright metal material, such as silver wire, the weaving being such as to cause the fibrous material to protrude between the reflecting material and forming protuberances of fibrous material larger than the infinitesimal areas of bright material, and the weaving being sufficiently loose to permit the transmission of sound.

Referring first to Figure 1, the fabric as a whole is indicated at 12, said fabric having binding 13, preferably loop-shaped in transverse section, to receive rods 14 which, in practice, have connected thereto means for stretching the fabric to very taut condition.

The important feature of my invention resides in the structure or composition of the woven fabric of the reflecting screen 12, said fabric consisting of warp strands 15 and weft strands 16. The warp strands 15 are of very fine bright reflecting material such as silver wire, while the weft strands 16 are of rather loose fibrous material such as cot-

ton. The weft strands are sufficiently larger and softer than the fine reflecting warp strands 15 to enable the latter to present infinitesimal reflecting spots or dots in depressions alternating with fibrous protuberances. A preferable way of effecting this is by so weaving that the warp strands 15 are in front of the weft strands with the latter in pairs and running behind some 10, more or less, of the weft strands 16 as illustrated by comparing Figures 2, 3 and 4. And, as illustrated by Figure 5, the upper margin of which represents the face of the fabric and the rear margin of which figure 10 represents the rear face of the fabric, the horizontal stretches of the strands 16 extend across six or seven, more or less, of the warp strands 15. The result of this structure or 15 its substantial equivalent is such that, in use, the light from the picture projector strikes small bright spots and is reflected onto the fibrous protuberances which materially exceed the bright material in front or face exposed area, resulting in so exhibiting 20 the picture that such picture is nearly as well viewed from an angular direction as from directly in front. This is because some of 25 the light is reflected from the fine bright spots somewhat against the sides of the 30 fibrous protuberances.

A very important feature of my invention resides in the fact that the fine interstices of the fabric permit the un-muffled transmission of sound to the audience from the usual 35 loud speakers mounted behind the screen.

A further advantage resulting from the employment of the fine metal wire is that, due to its inherent resonance, the screen as 40 a whole slightly vibrates in synchronism with the sound waves and therefore enhances the transmission of sound to the audience.

The present application is filed as a continuation in part of my co-pending application, Serial Number 346,513, filed March 13, 45 1929, which application is being abandoned in favor of the present application.

Having now described my invention, I claim:

1. A motion picture screen the surface of 50 which presents infinitesimal reflectors with soft fibrous material protruding between said reflectors and exceeding said reflectors in exposed area, said screen having interstices to facilitate the transmission of sound.
2. A motion picture screen the surface of 55 which presents infinitesimal areas of bright metal with larger protuberances of soft fibrous material, said screen having interstices to facilitate the transmission of sound.
3. A motion picture screen of soft woven 60 fibrous material having minute spots of bright metal exposed in depressions alternating with soft fibrous protuberances, said screen having interstices to facilitate the 65 transmission of sound.

4. A motion picture screen of woven material, the strands extending in one direction being of fine reflective material and the strands which traverse said fine strands being larger and of soft absorbent material and presenting protuberances alternating with the fine reflecting material. 70

5. A motion picture screen having alternating protuberances and depressions, the protuberances being composed of pairs of 75 soft strands of fibrous material and the depressions presenting small bright reflectors.

In testimony whereof I have affixed my signature.

CHESTER A. HARSON. 80
